UNITED STATES PATENT OFFICE

2,553,067

CURTAIN THREADER

Le Roy E. Thomas, Cleveland, Ohio

Application August 5, 1949, Serial No. 108,797

1 Claim. (Cl. 223—105)

1

This invention relates to curtain threaders.

An object of this invention is to provide a curtain threader adapted to be removably mounted on one end of a flat channel-shaped or tubular curtain rod, so that the rod may be extended into the hem or tunnel of the curtain without tearing or damaging the curtain.

Another object of this invention is to provide a curtain threader which is formed from wire and having a pair of loops or rings which will not only limit the extension of the device into the rod, but will also clamp the device onto the rod.

With the above and other objects in view, my invention consists in the arrangement, combination and details of construction disclosed in the drawing and specification, and then more particularly pointed out in the appended claim.

In the drawing,

Figure 1 is a plan view of a curtain threader constructed according to an embodiment of this invention,

Figure 2 is a side elevation of the threader in applied position,

Figure 3 is a side elevation of the threader removed from the curtain rod,

Figure 4 is a plan view of the device,

Figure 5 is a sectional view taken on the line 5—5 of Figure 1.

Referring to the drawing, the numeral 10 designates generally a V-shaped member which is formed of a strand of relatively stiff wire and the divergent arms 11 and 12 of the V-shaped member 10 have formed integral therewith loops or rings 13 and 14 respectively.

The ring 13 has extending therefrom an elongated arm 15 terminating in an eye 16, and the ring 14 has extending therefrom an arm 17 parallel with arm 15 and terminating in an eye 18.

In the use and operation of this device, the resilient arms 15 and 17 are extended into the end of a channel-shaped curtain rod R with rings 13 and 14 engaging on opposite sides of the rod R. The V-shaped member 10 will extend forwardly from the end of the rod R and the rings or loops 13 and 14 will provide a means for limit-

ing the extension of the arms 15 and 17 into the rod R. The lead member 10 is threaded or extended into the hem or tunnel of a curtain and will provide a means for opening this hem forwardly of the end of the rod R in order that the sharp corners of the rod R will not catch on the threads of the curtain or tear or pull the threads and hem as frequently happens where the rod is extended into the hem or tunnel without a threader as hereinbefore described. This threader is formed out of a single strand of relatively resilient wire so that it can be made at relatively small cost. The provision of the resiliently mounted arms 15 and 17 will permit the use of this threader in curtain rods of different sizes.

I do not mean to confine myself to the exact details of construction herein disclosed, but claim all variations falling within the purview of the appended claim.

What I claim is:

A curtain rod threader comprising a V-shaped member formed of resilient wire, a loop formed on the end of each of the divergent arms of said member, a pair of substantially parallel arms extending from said loops and engageable in an end of the curtain rod, and eyes formed on the ends of said latter named arms, each loop being formed of one convolution of the wire and engageable partly within and partly exteriorly of said curtain rod for limiting the extension of said loops into the end of the rod and providing lateral spreading of the hem of the curtain at the end of the rod.
